CLAIM

I claim the ornamental design for the two-armed lighting apparatus, as shown and described.

DESCRIPTION

FIG. 1 is a front, left, and top perspective view of the two-armed lighting apparatus;

FIG. 2 is a front elevational view of the two-armed lighting apparatus;

FIG. 3 is a rear elevational view of the two-armed lighting apparatus;

FIG. 4 is a left side elevational view of the two-armed lighting apparatus;

FIG. 5 is a right side elevational view of the two-armed lighting apparatus;

FIG. 6 is a top plan view of the two-armed lighting apparatus;

FIG. 7 is a bottom plan view of the two-armed lighting apparatus; and,

FIG. 8 is a front, left, and top perspective view of the two-armed lighting apparatus shown in a state of use.

The broken lines shown in the drawings depict portions of the article that form no part of the claimed design. The broken lines in FIG. 8 depict environmental structure and form no part of the claimed design.
